UNITED STATES PATENT OFFICE.

SIDNEY FRANC, OF NEW YORK, N. Y.

NECKTIE.

1,135,170.

Specification of Letters Patent. Patented Apr. 13, 1915.

Application filed November 18, 1913. Serial No. 301,673.

To all whom it may concern:

Be it known that I, SIDNEY FRANC, of New York, in the county of New York and State of New York, have invented certain new and useful Improvements in Neckties; and I do hereby declare the following to be a full, clear, and exact description of the invention, such as will enable others skilled in the art to which it appertains to make 10 and use the same.

This invention relates to improvements in neckties and more particularly to such as comprise tying ends which are wider than the intermediate neckband,—the object of 15 my present invention being to so construct a neck-tie of the type specified, as to facilitate the adjusting and tying of the same when used with turn-down collars.

A further object is to provide a neck-tie 20 with a neck-band portion which shall be strong and substantial in structure; which shall be readily movable between the folds of a turn-down collar during adjusting of the tie; and which shall operate to hold the 25 tie in place after it shall have been adjusted and tied.

With these objects in view, the invention consists in certain novel features of construction and combinations of parts as here- 30 after set forth and pointed out in the claim.

In the accompanying drawings, Figure 1 is a view of a necktie embodying my improvements, and Fig. 2 is a sectional view.

35 My improved tie comprises three portions or sections,—viz., end or tying sections 1, 1, and an intermediate neck-band section 2 of a different material. The end or tying sections 1, 1, may be made of any desired light 40 material such as silk, and each may be folded so as to present a general tapering appearance,—the smaller ends of said sections being united to the ends of the neck-band section by stitching.

45 The neck-band section 2, is a tubular woven or knitted fabric, the ends of which are preferably cut V-shaped and receive the narrow ends of the tie-ports or sections 1.

A lining or padding strip 3 of any suitable 50 material extends through the tubular neck-

band section and its ends project into the folded portions of the tying sections 1, 1. When the several parts of the tie shall have been assembled, they will be stitched together as at 4 along the beveled edges of the 55 V-shaped ends of the tubular neck-band section 2,—said stitches passing through said V-shaped ends of the tubular section 2; through the inserted narrow ends of the tying sections 1, 1, and through the lining or 60 padding strip 3 and thus serving to unite the tying sections with the tubular neck-band section and securing the lining against longitudinal displacement in the latter. The tubular neck-band section is so woven 65 that it will constitute a narrow flattened tube which will be capable of withstanding the pull necessary in manipulating neck-ties of this character when worn with turn-down collars, without injury to or distortion 70 of the more delicate material of the tying end portions 1, and while the said tubular neck-band section possesses great stability, still it may be slid between the folds of the collar with sufficient freedom to facilitate 75 necessary adjustment of the tie. The lining 3 passing through the tubular section 2 serves to keep the same flat and also to prevent undue stretching of the tubular fabric.

Having fully described my invention what I claim as new and desire to secure by Letters Patent, is:—

A necktie comprising tying members, each composed of comparatively light-weight 85 material, an intermediate neck-band member composed of woven material made in the form of a flat tube, the ends of said tube receiving and secured to the respective tying members, and a strip passing 90 freely through said tubular member and entering the tying members.

In testimony whereof I have signed this specification in the presence of two sub-scribing witnesses.

SIDNEY FRANC.
